UNITED STATES PATENT OFFICE.

HENRI PATAUD, DECEASED, LATE OF PARIS, FRANCE; BY MARIE LOUISE MELANIE JOSEPHINE PATAUD, NÉE DE SALLS, OF PARIS, FRANCE, HEIRESS IN TRUST.

DEVICE ADAPTED TO DIMINISH THE WEAR OF PARTS OF CERTAIN ELASTIC TIRES.

1,127,803.

Specification of Letters Patent.

Patented Feb. 9, 1915.

Application filed April 18, 1912. Serial No. 691,734.

To all whom it may concern:

Be it known that HENRI PATAUD, late a citizen of the Republic of France and a resident of 15 Rue de la Fédération, Paris, France, but now deceased, did invent certain new and useful Improvements in Devices Adapted to Diminish the Wear of the Parts of Certain Elastic Tires, (for which a patent has been obtained in France on August 4, 1911, under No. 430,190,) of which the following is a specification.

This invention relates to elastic tires for vehicle wheels of the type in which the flexibility is derived from an endless chain which is stretched circumferentially on the periphery of the wheel and it has for its object to diminish the slackening of the chain which results from the rapid wear of certain parts, by substituting wherever it is possible rolling displacement to sliding displacement.

With this object in view the invention consists on the one hand in forming and mounting certain links of the chain in such a manner that all the displacements of the links with relation to their pins or to their adjacent links result in a rolling motion and on the other hand the invention consists of a system of mounting the chain on the wheel in such a manner that all relative displacements of the parts be transformed to a displacement of the parts supporting the chain with relation to the fixed rim and that these displacements be produced only by rolling without sliding or in such a manner that if some of the displacements by sliding exist, the contact pressure of the parts that support it may be as weak as desired and the wear resulting from this frictional sliding does not affect the tensions of the chain.

In the accompanying drawings given by way of example: Figures 1, 2, 3 and 4 are diagrams of the equilibrium positions of the new link. Fig. 5 is the diagram of the displacements of the different links of the arrangement according to the invention. Fig. 6 is a diagram showing the necessity of giving to certain links the particular forms illustrated. Fig. 7 is a mounting diagram of similar parts to those employed in the mounting system according to the invention but which do not produce the same result. Fig. 8 shows a type of pin support affording a rotation for a sliding of said

part with relation to the fixed rim. Fig. 9 shows a type of pin support affording displacements by rolling of said support with relation to the fixed rim. Figs. 10 and 11 show a type of pin support affording displacements by rolling with a guiding of the movable part. Figs. 12, 13, 14, 15 and 16 are diagrams of different ways of realizing the invention. Fig. 17 shows a fraction of a tire embodying the devices forming the object of the invention.

The devices forming the object of the invention are combined as stated so as to diminish these wearings by substituting as far as possible rolling displacements to sliding displacements.

The device according to the invention is to assure the displacement of the link *f* on the pins *b* and *d* or inversely by a double rolling. It is remarkable by the fact that the links *f* are formed in such a manner that the surfaces on which the pins *b* and *d* are to roll shall be diametrical opposed arcs of a same circle. Besides, the pins *b* and *d* that bear merely on said arcs are prevented from turning with relation to the parts *a* and *c* respectively by being keyed for instance on said parts and finally the supports *a* are arranged so as not to receive any effort but by means of the pins *b* and *d*. It will indeed be shown that the combination of these three means is necessary and sufficient to obtain the double rolling searched for.

I will first examine the conditions for the equilibrium of a link *f* entirely round or having two concentric circular bearings, as the one illustrated in Fig. 5, according to the actions and reactions to which it is submitted. An exterior effort may be applied either to one of the pins *b* or *d*, either or both, or to *f*. Any effort transmitted from the pins to the link *f* or inversely is transmitted according to the common normal line to the circles of the cross sections of said two parts.

If the effort *F* (Fig. 1) is applied to *d*, the reaction *F'* occurs at *b*, and if no force is applied directly to *f*, all the positions of stable equilibrium of the system will be of the kind of that illustrated in Fig. 1 in which the action and reaction are equal and opposed on the direction of a common normal line to the three circumferences. In this position indeed, the system is statically in

equilibrium since it is submitted to two equal and opposed forces and this equilibrium is stable because if said pins abandon their equilibrium position under the action of additional force, they will recover it when said force will disappear. On the contrary an equilibrium position such as the one illustrated in Fig. 2 would not correspond to a stable equilibrium since the component forces F^2 are annulled by the rigidity of the link f and the components F^3 tend to bring back the system to the position of Fig. 1. If the action is applied to f and the reactions to b and d or inversely, the position illustrated in Fig. 3 will be an equilibrium position, on the condition that, as in the case of the figure, the resultant F of the reactions of the pins on the circle is directly opposed to the action. Finally, the position illustrated in Fig. 4 is not an equilibrium position in this case, since it would be necessary that the reactions F' be infinite. Even if the pins b and d are mechanically connected together so as not to be able to approach one the other, the equilibrium position will be of the kind illustrated in Fig. 3, but extremely close to that of Fig. 4. This being admitted, consider a link f (Fig. 5) comprising two bearing portions diametrically opposed and situated in a same circumference, this link being mounted on the two pins b and d in the conditions above stated, and suppose that the effort 2^P is applied on the part c which connects the two adjacent pins d . The system will then assume the position $b' f' d' c'$ and the effort 2^P will be transmitted by halves to each of the pins d . The effort P applied to one of the pins d will be decomposed in two, the one P' annulled by the part c and by the symmetrical effort of the other pin d , and the other P^2 normal with the circle of the link f' . The system being in equilibrium and the effort being applied to d , without a force being applied directly to the link f , the circumference of the cross section of the pin b' will be tangent to the interior circle of f' on a point diametrically opposed to the contact point of d' and of said circle, and the reaction b' on the circle f' will be Q directed according to the normal line common to both circles. This reaction will be decomposed in two, the one Q' provided by the tension of the chain and the other Q^2 provided by the reaction of the support a . It will now be shown that the system $b f d$ may come to this new position $b' f' d'$ by simultaneous rolling of the pins b and d on the bearing surfaces of the link f . This way of displacement meeting with a resistance which is infinitely less than the one of sliding, it is obvious that it will be that one which will take place. For that purpose, it will be shown that the movement which brings the parts $b f d$ to the positions $b' f'$

d' may be decomposed into two rolling motions, one of b on f and the other of d on f and that these two rolling motions may be produced simultaneously. Now, these two movements may be produced simultaneously since they assure rotations of the link f in the same direction and their superposition brings the parts $b f d$ to $b' f' d'$.

The combination of means above stated is necessary and if all these means are not employed simultaneously, the double rolling can not be produced. Indeed, if the two bearing surfaces of f are not in a same circle, the normal lines to the points of contact with the parts b and d (Fig. 6) will not always be in the prolongation one of the other and there will be no equilibrium after a certain rolling, since the forces P^2 and Q will tend to place themselves in the prolongation one of the other and the parts will assume their equilibrium position by sliding. If the pins can turn with relation to the parts a and c , there is rotation by sliding with relation to said parts. It is also obvious that said pins must only be resting on the bearings of the link f . To show the necessity of the relative positions stated it will be supposed that the link with two concentric circular bearing surfaces, instead of replacing the link f , will replace any of the parts a and c , as illustrated in the second hypothesis in Fig. 7; the effort being applied to the link f itself and the reactions to the pins, the stable equilibrium position will be that of the kind shown in Fig. 3. Now it may be seen in the figure that the displacement of the part u determines rotations of the pins b and d in directions opposite one the other. If said pins roll on the two bearings of the part u , the latter will be at u^2 and the pins at d^2 . Well this is not an equilibrium position, since the resultant of the reactions of the pins on the circle is in the direction of the force. Therefore the part u will assume by sliding an equilibrium position u' , the pins coming at d' . In the practice, this sliding and the rotations take place simultaneously by infinitely small values and can be assimilated to a rotation by sliding of the pins in one point of their bearing surface on the part u .

It will be remarked that chains with entirely round links are already known, that is to say chains satisfying the first of the conditions required for a double rolling; but it will be shown that the two other conditions hereabove mentioned have never been realized simultaneously with these chains, and that consequently, the use of chains of this kind has never permitted to realize the advantages aimed by the invention. Indeed, a link of such a chain is mounted either on two pins or on two links; if the effort or the reaction is applied to the

pin or to the adjacent link, the latter will turn with relation to the link considered which remains stationary; therefore one of the conditions is not fulfilled if the effort or 5 the reactions is applied to the link itself, which is the case just examined in which the relative position of the parts are bad and where no rolling can take place. Thus, the chains with round links do not avoid the 10 displacement by sliding in the various applications where they are employed.

The principle of the improvements that 15 will now be described consists in replacing the displacement of the chain with relation to its supports by a displacement of the supports with relation to the fixed rim, only one 20 of said supports being invariably secured to said rim.

A first improvement, Fig. 8, consists in 25 mounting the pins *b* fixedly in supports *m* capable of oscillating about pins *k* mounted all on an iron circle *h* secured to the wheel, which facilitates the movement of the pins *b* but determines a rapid wear of the bearing surfaces of the supports *m* on their pins *k* and of the pins *k* themselves.

Fig. 9 represents a mounting system in 30 which the displacements of the supports with relation to the circle *h* are entirely obtained by rolling without sliding. In this system, the pins *b* are fixed with relation to a support *g* which only rests on the rim upon the circle *h* or upon an intermediate part. Said support *g* is kept in a radial position 35 by the stretched chain and transversely by locating itself for instance just between the two hooks of the rim.

To enable the support *g* to roll on the circle *h* when the pin *b* comes to *b'* it is only 40 necessary that the curves of the cross sections of the bearing surface of *g* and of the circle *h* have not the same radius of curvature. In the example illustrated in Fig. 9, the cross section of the support *g* is a circle 45 and the center of the pin *b* coincides with the center of said circle. When this last condition is realized, the action of the support *g* on the iron circle is always directed according to the normal line *N* common to both curves of the cross sections and the two 50 surfaces roll one on the other when *b* comes to *b'* without any sliding movement taking place.

If the center of the pin *b* does not coincide with the center of the circle of cross section of the support *g*, Fig. 10, or if the support *g* has, as cross section for its bearing surface, any other curve than a circle, the effort exerted between the bearing surfaces of the support *g* and of the circle *h* is 55 no more directed according to the normal line common to two curves of the cross sections of the bearing surfaces and results therefore in a component *F'* which tends to cause the two surfaces to slide one on the other.

in antagonism with the adhesion effort of both surfaces. To be certain, however, that the displacement is still produced by rolling in this case, it will only be necessary to force one point of the support *g* to move along a 70 curve of such a form that the only possible movement between *g* and *h* be a rolling movement. This curve will be the roulette of the curve of the cross section of *g* with relation to the curve of the cross section of *h* 75 taken from a certain point of the support *g* for instance with relation to the end of the heel forming the bearing surface of *g* upon *h*. This is the case that has been illustrated in Fig. 11 in which said wheel is comprised 80 between two parts *l* and *l'* having as cross sections the roulettes described by its two ends and assuring consequently the rolling in the two directions. In this case, the component *F'* of the sliding movement when it has a 85 higher value than that of the adhesion between the support *g* and the circle *h*, is destroyed by the permanent bearing of the end of the heel of *g* against the guide part. This bearing determines a frictional sliding during the displacement of the support *g*, but the intensity of this frictional sliding may take the value desired because the more the curve of the cross section of *g* approaches the circular form and the more the center of 90 *g* approaches the center of this circle, the more the component of said frictional sliding diminishes until it becomes null as it has been observed when these two conditions are realized simultaneously. Besides the wear 95 resulting from said frictional sliding has no influence on the tension of the chain since it does not diminish the height of the bearing of the pins *b*. If guiding parts *l* *l'* are provided for the device, the bearing surfaces of 100 the support *g* and of the circle *h* may assume the different forms diagrammatically illustrated in Figs. 12 to 16.

A complete element of the elastic chain tire embodying the two devices which form 110 the object of the present invention will then be constituted as illustrated in Fig. 17. The supports *G* are placed upon the flat rim *H* of the wheel and guided by two parts *L* *L'* made solid with the rim. The curve of 115 the cross section of said parts *L* *L'* is traced as stated above and the latter are ended by a nose adapted to limit the amplitude of the possible oscillation. To give to the chain the tension required, the supports *G* carry 120 parts *S* in which are fixed the pins *B*. These parts *S* fit exactly over the upper end of the supports *G*, and the height required for the pins *B* is controlled by inserting wedges *l* between the supports *G* and the parts *S*. 125 The links *F* bear against the pins *B* by one of their bearing surfaces and by the other against the pins *D* made solid with the parts *C* which support the efforts. In this system of mounting, all the conditions above set 130

forth are realized, and the working is the one referred to as resulting in a considerable diminution of the wear.

The tread as illustrated in Fig. 17 consists of a second chain stretched at the same time as the first, its supports corresponding to the suspended points of the first. This second chain may be advantageously made in a similar manner to that described for the 10 main chain, that is to say may comprise links P similar to the links F and arranged between the parts C and Q. These parts which form the elements of the tread are shown provided with projections or rivets N.

Having now described the invention, what is claimed as new and desired to be secured by Letters Patent is:

1. An elastic tire for wheels of vehicles of the kind in which the flexibility is derived 20 from an endless chain which is stretched circumferentially on the periphery of the wheel, comprising in combination a fixed rim, supports arranged on said rim, pins carried by said supports, chain links having two bearing surfaces the cross section of 25 which appears as two diametrically opposed arcs of a same circle, and a tread connected to said chain links, substantially as described and for the purpose set forth.

2. An elastic tire for wheels of vehicles of the kind in which the flexibility is derived 30 from an endless chain which is stretched circumferentially on the periphery of the wheel, comprising in combination a fixed rim, supports pivoted to said rim, pins carried by said supports, chain links having two bearing surfaces the cross section of 35 which appears as two diametrically opposed arcs of a same circle, and a tread connected to said chain links, substantially as described and for the purpose set forth.

3. An elastic tire for wheels of vehicles of the kind in which the flexibility is derived 40 from an endless chain which is stretched circumferentially on the periphery of the wheel, comprising in combination a fixed rim, supports arranged on said rim, pins carried by said supports, chain links, having two bearing surfaces the cross 45 section of which appears as two diametrically opposed arcs of a same circle, and which bearing surfaces are adapted to roll about said pins, intermediate parts inserted between said chain links and provided with 50 pins, and a tread connected to said intermediate parts, substantially as described and for the purpose set forth.

4. An elastic tire for wheels of vehicles of the kind in which the flexibility is derived 50 from an endless chain which is stretched circumferentially on the periphery of the wheel, comprising in combination a fixed rim, supports having a bearing surface 55 formed of an arc of a circle resting all loosely on said rim, except one which is

fixed to the latter, pins carried fixedly by said supports, chain links having two bearing surfaces the cross section of which is formed by two diametrically opposed arcs of a same circle and a tread connected to 70 said chain links, substantially as described and for the purpose set forth.

5. An elastic tire for wheels of vehicles of the kind in which the flexibility is derived 75 from an endless chain which is stretched circumferentially on the periphery of the wheel, comprising in combination a fixed rim, supports resting loosely on said rim and having a bearing surface the cross section of which is formed by a curve having 80 a different radius of curvature than the one of the rim, one of said supports being fixed to said rim, pins carried fixedly by said supports, chain links having two bearing surfaces the cross section of which appears as two diametrically opposed arcs of a same circle, intermediate parts inserted between 85 said chain links and provided with pins made solid with said parts, and a tread connected to said intermediate parts, substantially 90 as described and for the purpose set forth.

6. An elastic tire for wheels of vehicles of the kind in which the flexibility is derived 95 from an endless chain which is stretched circumferentially on the periphery of the wheel, comprising in combination a fixed rim, supports resting loosely on said rim and having a bearing surface the cross section of which is formed by a circle having a 100 different radius than the one of the rim, one of said supports being fixed to said rim, pins carried fixedly by said supports, chain links having two bearing surfaces the cross section of which appears as two diametrically opposed arcs of a same circle, and a tread connected to said chain links, substantially 105 as described and for the purpose set forth.

7. An elastic tire for wheels of vehicles of 110 the kind in which the flexibility is derived from an endless chain which is stretched circumferentially on the periphery of the wheel comprising in combination a fixed rim, supports resting loosely on said rim 115 and having a bearing surface the cross section of which appears as a curve having a different radius of curvature than the one of the rim, one of said supports being fixed to said rim, pins carried fixedly by said supports, guiding parts formed in the rim and having as cross section the roulettes described by the ends of the curved part formed in the supports, chain links having 120 two bearing surfaces the cross section of which appears as two diametrically opposed arcs of a same circle, and a tread connected to said chain link, substantially 125 as described and for the purpose set forth.

8. An elastic tire for wheels of vehicles of 130

the kind in which the flexibility is derived from an endless chain which is stretched circumferentially on the periphery of the wheel, comprising in combination a fixed 5 rim, supports resting on said rim and having a bearing surface the cross section of which appears as a curve having a different radius of curvature than the one of the rim, one of said supports being fixed to 10 said rim, adjustable parts mounted on said supports, pins carried fixedly by said adjustable parts, guiding parts formed in the rim and having as cross section the roulettes described by the ends of the curved part

formed in the supports, chain links having 15 two bearing surfaces the cross section of which is formed by two diametrically opposed arcs of a same circle, and a tread connected to said chain links, substantially as described and for the purpose set forth. 20

In testimony whereof, I have signed my name to this specification in the presence of two subscribing witnesses.
